CHEESE KEEPER

Lawrence H. Wilson, Detroit, Mich., assignor to Admiral
Corporation, Chicago, Ill., a corporation of Delaware

Application June 17, 1954, Serial No. 31,060

Term of patent 14 years

(Cl. D67—3)

To all whom it may concern:

Be it known that I, Lawrence H. Wilson, a citizen of the United States, residing at Detroit, in the county of Wayne, State of Michigan, have invented a new, original, and ornamental Design for a Cheese Keeper, of which the following is a specification, reference being had to the accompanying drawings, forming a part hereof.

Fig. 1 is a front elevational view of a cheese keeper, showing my new design;

Fig. 2 is a top plan view of the same;

Fig. 3 is a rear elevational view thereof; and

Fig. 4 is a side elevational view of the same.

I claim:

The ornamental design for a cheese keeper, as shown.
